Primary Examiner — Dana K Weiland*Assistant Examiner* — JennyLou M Binas(74) *Attorney, Agent, or Firm* — Haynes Beffel & Wolfeld LLP; Ernest J. Beffel, Jr.; Paul A. Durdik(57) **CLAIM**

The ornamental design for a home robot, as shown and described.

DESCRIPTION

FIG. 1 is a top, right perspective view of a home robot showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines show portions of the home robot that form no part of the claimed design.

1 Claim, 7 Drawing Sheets(56)
